(57) **CLAIM**

The ornamental design for a display screen portion with animated graphical user interface, as shown and described.

DESCRIPTION

FIG. 1 is the first image in a sequence for a display screen portion with animated graphical user interface showing my new design;

FIG. 2 is a 2nd image thereof;

FIG. 3 is a 3rd image thereof;

FIG. 4 is a 4th image thereof;

FIG. 5 is a 5th image thereof;

FIG. 6 is a 6th image thereof; and,

FIG. 7 is a 7th image thereof.

The broken lines showing a display screen portion and elements of the graphical user interface illustrate portions of the article, and form no part of the claimed design. The appearance of the animated graphical user interface transitions sequentially between the images shown from FIGS. 1-7. The process or period in which one image transitions to another forms no part of the claimed design.
